UNITED STATES PATENT OFFICE.

LUKE W. FARMER, OF SOMERVILLE, MASSACHUSETTS.

APPARATUS FOR FORMING PAPER CUPS.

1,107,506.

Specification of Letters Patent. Patented Aug. 18, 1914.

Application filed August 23, 1912. Serial No. 716,584.

To all whom it may concern:

Be it known that I, LUKE W. FARMER, a citizen of the United States, residing at Somerville, in the county of Middlesex and State of Massachusetts, have invented an Improvement in Apparatus for Forming Paper Cups, of which the following is a specification.

In the manufacture of one of the numerous types of paper cups now on the market, a double bottom is employed, and the lower edge of the cup-body is turned over upon the first bottom-piece, and then the second bottom-piece is applied.

This invention has for its object to construct an apparatus adapted to turn the lower edge of the cup-body over onto the first bottom-piece, and involves the employment of a flanging-tool designed to be manipulated by hand. The first bottom-piece and cup-body are placed on a rotatable form and said form is arranged on a turret or other rotatable carrier, whereby it may be moved into coöperative relation with the flanging-tool, and means are provided for rotating said form while in such position, in order that the flanging-tool while held in a certain position may act to turn inward the lower edge of the cup-body.

Figure 1 is a side elevation of a portion of a cup-forming apparatus embodying this invention. Fig. 2 is a horizontal section of the same taken on the dotted line 2—2, Fig. 1. Fig. 3 is a vertical sectional detail taken on the dotted line 3—3. Fig. 2. Fig. 4 is a detail of the flanging-tool, illustrating the operation of the same when turning over the lower end of the cup-body. Fig. 5 is a vertical section of a completely formed cup.

10 represents one of a plurality of conical forms on which the cups are formed. It is secured to a spindle 12 having its bearings in the extremity of an arm 13, extended radially from a hub 14. Said hub is mounted on a pivot-stud about which it is free to be rotated by hand, and from it several arms extend radially, each supporting a form 10. The spindle 12 has secured to it a spur-gear 20, which, when engaged by a driven-gear 50 rotates the form. A single driving-means is provided into and out of engagement with which the several spur-gears are movable, thereby to rotate the forms separately. The driving-means is movable into and out of the path of movement of said spur-gear. As a driving means here shown, a pinion 25

is mounted on a pivot-stud 26, secured to a short arm 27, extended radially from an upright rod 28, said rod having its bearings in a tubular support 29. Said pinion 25 has 60 connected with it another pinion 30, which engages a pinion 31, secured to an upright rotating-shaft 32 arranged in alinement with the rod 28. Said pinions 25 and 30 are movable planetarily about the pinion 31, by 65 a rotary movement of the rod 28, thereby to move the pinion 25, into and out of the path of the spur-gear 20, while the pinion 30 remains in continuous engagement with the pinion 31. As a means to oscillate the rod 70 75 70, for the purpose of moving the pinion 25, planetarily about the pinion 31, a hand-piece 40 is secured to the upper end of the rod 28 which is conveniently arranged to be engaged by one hand of the operator. By the means thus described the forms will be rotated separately.

The essential feature of my invention, however, resides in a flanging-tool, here shown as a blade 50, secured to the hand-piece 40, or it may be otherwise connected to the rod 28, so as to be moved by the hand-piece in a direction toward the form in a horizontal plane or thereabout, and at the same time the rod is turned to engage the gearing.

In operation the bottom-piece 60, is placed on the form; then a cup-body is placed on the form with its small end portion projecting a short distance above the top of the 90 form; then the hand-piece 40 is moved to cause engagement of the gearing, and the form thereby caused to rotate, and the flanging-tool is moved to engage the projecting portion of the cup-body and turn said projecting portion inward upon the bottom-piece, as represented in Fig. 4; then the other bottom-piece is applied. Suitable means are usually employed to apply a moderate pressure to the bottom-piece, and, as 100 here shown, a pivoted plate 70, is arranged to be swung downward into engagement with the bottom-piece to clamp the parts firmly and hold them for a short period of time. Said clamping-plate 70, is moved 105 downward by means of a hand-lever 71, and when thus moved a projecting portion 72, thereon engages the upper end of a pivoted lever 73 to move said lever from the full into the dotted line position shown in Fig. 110 1. As such movement of the clamping-plate causes the pivotal connection 75, to pass

through and beyond the plane containing the pivots 76 and 77, said clamp will remain in such position until the turret or carrier is rotated far enough to swing the 5 end of the lever 78 into engagement with a cam 80, by which it is moved to exert a moderate pressure upon the hand-lever 71, sufficient to cause the pivotal connection 75 to pass to the other side of said plane containing 10 the pivots 76 and 77, whereupon the spring 85 acts to lift the clamping-plate.

I claim:—

15 In an apparatus for forming paper cups, the combination with a rotatable form on which a bottom-piece and cup-body are placed, a carrier for said form, a gear operatively actuating said form, a pinion, a movable support for said pinion affording move-

ment thereof into and out of engagement with said gear, another pinion connected 20 with the aforesaid pinion, a driving gear for said last named pinion about which said pinion is movable planetarily, an oscillatory rod bearing said movable support, and a flanging tool attached to said rod and movable to engage the bottom of the cup-body when said rod is turned, whereby to turn the bottom of the cup-body inward as the form is rotated.

In testimony whereof, I have signed my 30 name to this specification, in the presence of two subscribing witnesses.

LUKE W. FARMER.
